UNITED STATES PATENT OFFICE.

WILLIAM FROST, OF LONDON, ENGLAND, ASSIGNOR TO HARVEY FROST & COMPANY, LIMITED, OF LONDON, ENGLAND.

PORABLE VULCANIZER.

1,360,962.

Specification of Letters Patent. Patented Nov. 30, 1920.

Application filed March 1, 1920. Serial No. 362,181.

To all whom it may concern:

Be it known that I, WILLIAM FROST, a subject of the King of England, residing in London, England, have invented certain new 5 and useful Improvements in Portable Vulcanizers, of which the following is a specification.

This invention is for improvements in or relating to portable vulcanizers particularly 10 adapted for tire-repairs, and has for its object to provide a vulcanizer whereof the vulcanizing surface shall be brought nearer to the heating-chamber than has heretofore been possible.

15 According to this invention a portable vulcanizer, of the type wherein a detachably secured molding-plate constitutes one wall of the heating-chamber, is characterized by the said molding-plate being of circular form 20 and by the steam-chamber being provided with a neck having a circular flange around it to receive bolts for securing the molding-plate to the heating-chamber.

This invention is particularly applicable 25 to vulcanizers for solid tires where considerable heat is required and also considerable pressure, and a further feature of the invention relates to clamping-means for thrusting the vulcanizer with the necessary pressure 30 against the tire to be repaired.

In the accompanying drawings which illustrate one method of carrying out this invention:—

Figure 1 is a front view of the vulcanizer 35 without its heating apparatus and with the molding-plate detached;

Fig. 2 is a side elevation of the same, with the molding-plate secured in place;

Fig. 3 is a central vertical section through 40 Fig. 1 on the line 3—3;

Fig. 4 is a face view of the molding-plate;

Fig. 5 is a section through the same on the line 5—5 of Fig. 4, and

Fig. 6 is a perspective view of the vulcanizer clamped in position on a tire.

The same letters indicate the same parts throughout the drawings.

The vulcanizer comprises a steam-chamber A which is in communication with a steam-generating chamber A¹. The steam-generating chamber may be heated by means which are not shown in the drawings and constitute no part of the present invention, but tubes A² are indicated for the passage of the hot gases of combustion from a suitable burner.

The front portion of the steam-chamber is made to overhang the steam-generating chamber so that a forwardly-projecting neck A³ is provided having a surrounding circular flange A⁴. The flange is provided with a series of notches A⁵ to receive bolts as herein-after described, and the front wall of the steam-chamber is provided by a molding-plate B having notches B¹ corresponding to the notches A⁵.

The front face of the molding-plate is shaped to correspond to the particular tire and to the particular part of that tire with which it is intended to be used, and a series of these plates would be provided for each vulcanizer, so that various makes of tire and different parts of the same could be vulcanized with the same vulcanizer.

The back of the plate is roughened at the edges as shown at B², Fig. 5, to receive packing to make a joint with the flange A⁴; the flange also may be roughened if desired.

The interior of the steam-chamber A is strengthened by webs A⁷ radiating from a central boss A⁶, and in this central boss is secured a screw-threaded stud C. The back of the steam-chamber is made flat and it is set in from the back of the steam-generating chamber, so that a square shoulder C¹ is provided.

To secure the vulcanizer in place for effecting a tire repair, a clamp is employed comprising an outer bridge-piece D which is webbed along the center to stiffen it and is provided with a central boss D¹ to receive the stud C. The bridge-piece is fixed to the vulcanizer by a wing-nut D² which is screwed on to the end of the stud C and the side of the bridge-piece lies against the shoulder C¹ provided by the steam-generating chamber.

The ends of the bridge-piece are slotted as shown at D³, two slots being provided at each end, which slots receive bolts E from coöperating bridging-rods E¹. The rods are provided with a series of perforations E² and the bolts E are bifurcated at their ends and receive pins E³ which can be inserted in any one of the holes E².

As will be seen from Fig. 6, the vulcanizer can be clamped in position by the bridge-piece D and bridging-rods E¹ connected to the bridge-piece by the bolts E, and the length of these bolts together with the slots D³ and the holes E² in the bridging-rods, allow of considerable adjustment for

different sized tires and makes of rim. By screwing up the nuts on the bolts E, the vulcanizer can be forced upon the tire with considerable pressure.

5 When about to effect a repair, all the operator has to do is to select a molding-plate B whose shape suits the tire and the part of it which is to be repaired, and then to fix this plate to the steam-chamber by 10 means of bolts and nuts F, see Figs. 2 and 5. The nuts need never be separated from the bolts as they are slipped laterally into place into the notches A⁵ of the steam-chamber flange A⁴ and the notches B¹ of the 15 molding-plate B. A little packing material is provided between the opposed faces of these two parts and thus when the bolts are screwed up tight, a steam-tight joint is effected.

20 What I claim as my invention and desire to secure by Letters Patent is:—

1. In a vulcanizer of the character described, the combination of a heating chamber comprising a steam-generating chamber, and a steam-chamber that has a circular flange and is connected with the steam-generating chamber by a neck, and a circular molding plate detachably bolted to 25 said flange.

30 2. In a vulcanizer of the character described, the combination of a heating chamber comprising a steam-generating chamber, and a steam-chamber that has a circular flange at the front, is connected with the 35 steam-generating chamber by a neck and carries at the back a rearwardly-projecting stud, a circular molding plate detachably bolted to said flange, and clamping means detachably attached to said stud.

3. In a vulcanizer of the character de- 40 scribed, the combination of a heating chamber comprising a steam-generating chamber, and a steam-chamber that has a circular flange at the front, is connected with the steam-generating chamber by a neck and 45 carries at the back a rearwardly-projecting stud, a circular molding plate detachably bolted to said flange, and clamping means comprising two bridge-pieces and bolts de- 50 tachably connecting the same together, whereof one bridge-piece is detachably at- tached to said stud.

4. In a vulcanizer of the character de- 55 scribed, the combination of a heating chamber comprising a steam-generating chamber, and a steam-chamber that has a circular flange at the front, is connected with the steam-generating chamber by a neck and 60 carries at the back a rearwardly-projecting stud, which steam-chamber is set forward 65 relatively to the steam-generating chamber so that a shoulder is provided at the back of the steam-chamber, a circular molding plate detachably bolted to said flange, and clamp- 70 ing means bearing against said shoulder and 75 detachably attached to said stud.

5. In a vulcanizer of the character de- 70 scribed the combination of a heating chamber comprising a steam-generating chamber, and a circular steam-chamber that has a 75 circular flange and is connected with the steam-generating chamber by a neck, said steam-chamber having radial strengthening webs connecting one end wall with the sides of the chamber, and a circular molding plate detachably bolted to said flange.

In testimony whereof I affix my signature.
WILLIAM FROST.
